[57] **CLAIM**

The ornamental design for a comb, as shown and described.

DESCRIPTION

FIG. 1 is a top plan view of a comb showing my new design;
FIG. 2 is a rear elevational view thereof;
FIG. 3 is a right side elevational view thereof;
FIG. 4 is a left side elevational view thereof;
FIG. 5 is a front elevational view thereof, the broken lines showing the comb teeth are for illustrative purposes only, and form no part of the claimed design; and,
FIG. 6 is a bottom plan view thereof.
